US00D622722S

(12) **United States Design Patent**
Green et al.

(10) **Patent No.:** US D622,722 S
(45) **Date of Patent:** ** Aug. 31, 2010

(54) **ELECTRONIC READER DEVICE**

(75) Inventors: **Chris Green**, San Francisco, CA (US); **John E. Johnston**, Redwood City, CA (US); **Jonah Avram Becker**, San Francisco, CA (US); **Jeffrey Scott Croyle**, San Francisco, CA (US); **Bernhard Wildner**, San Francisco, CA (US); **Youenn Herve Yann Colin**, San Francisco, CA (US); **Derek Jenchia Loh**, Foster City, CA (US); **Audrey Caroline Christine Louchart**, Seattle, WA (US)

(73) Assignee: **Amazon Technologies, Inc.**, Reno, NV (US)

(**) Term: **14 Years**

(21) Appl. No.: **29/343,722**

(22) Filed: **Sep. 17, 2009**

CLAIM

The ornamental design for an electronic reader device, as shown and described.

DESCRIPTION

FIG. 1 is a perspective view of the electronic reader device; FIG. 2 is a front elevation view of the electronic reader device of FIG. 1;

FIG. 3 is a back elevation view of the electronic reader device of FIG. 1;

FIG. 4 is a bottom plan view of the electronic reader device of FIG. 1;

FIG. 5 is a top plan view of the electronic reader device of FIG. 1;

FIG. 6 is a left side elevation view of the electronic reader device of FIG. 1; and,

FIG. 7 is a right side elevation view of the electronic reader device of FIG. 1.

The broken lines are directed to environment and are for illustrative purposes only. The broken lines form no part of the claimed design.
